ROTARY DISK CUTTER

Giovanni Parovel, Sacramento, Calif.

Application January 30, 1948, Serial No. 5,339

1 Claim. (Cl. 144—219)

1

This invention is directed to, and it is an object to provide, a bowling alley finishing machine of novel construction and operation.

Another object of the invention is to provide a bowling alley finishing machine which includes a novel rotary scraper assembly adapted to work on the alley to level the same with advance of the machine therealong; the machine being supported and guided by rails temporarily mounted in the gutters alongside the alley.

An additional object of the invention is to provide a machine, as above, wherein the rotary scraper assembly includes a pair of vertical axis, rotary scrapers mounted in side by side relation, and having projecting blades whose paths lap, to the end that no portion of the alley is skipped between such rotary scrapers. The invention also provides an effective mount and drive for the rotary scrapers.

A further object of the invention is to provide a bowling alley finishing machine which comprises, in combination, a rotary scraper assembly, and a powered sanding drum; such instrumentalities cooperating to accurately level and finish the surface of bowling alleys.

A further object of the invention is to produce a practical and reliable bowling alley finishing machine, and one which will be exceedingly effective for the purpose for which it is designed.

These objects are accomplished by means of such structure and relative arrangement of parts as will fully appear by a perusal of the following specification and claim.

In the drawings:

Fig. 1 is a side elevation of the improved bowling alley finishing machine.

Fig. 2 is a cross section on line 2—2 of Fig. 1.

Fig. 3 is an enlarged fragmentary, sectional elevation of one of the rotary scrapers including its mount and drive.

Fig. 4 is a fragmentary sectional plan view illustrating the relative positions of the rotary scraper assembly, and the sanding drum.

Referring now more particularly to the characters of reference on the drawings, the machine comprises a rigid housing 1 which forms the main frame of the machine; such housing being open at the bottom and including side plates 2 and a top plate 3, the latter being rounded down at opposite ends of the machine to complete the housing enclosure.

The housing 1 is supported, for longitudinal travel, by a pair of transversely spaced wheels 4 at one end of the housing, and another pair of transversely spaced wheels 5 at the opposite end of the housing; all of said wheels, in the present

embodiment, being flanged, as shown, and for the purpose hereinafter described.

The machine is adapted to travel lengthwise of a bowling alley A above the surface thereof, and such machine is supported and guided on rails 6 temporarily mounted in the gutters 7. The rails 6 are carried on longitudinally spaced suspension brackets 8 which run out of the troughs, and include an adjustment screw 9 which bears on a shim block 10 seated on the floor to the side of the adjacent gutter 7 opposite the alley A. By adjustment of the screws 9 the rails 6 can both be set exactly level; said rails 6 then supporting the machine for travel likewise in a level path.

15 The flange wheels 4 and 5 ride the rails 6 in the manner illustrated in Figs. 1 and 2.

Between the wheels 4 and 5 the machine carries a pair of transversely spaced, rotary scrapers, each of which is indicated generally at 11. As the rotary scrapers 11 are each of identical construction, a description of one will suffice for both.

20 Each rotary scraper 11 comprises a horizontal, vertical axis spinner 12 which includes a hub 13, spider legs 14, and a peripheral band 15. At circumferentially spaced points, here 90° apart, the spinner 12 is radially slotted, as at 16, with said slots opening downwardly and outwardly. A flat blade 17 is engaged in each slot 16 in a vertically disposed, radially extending position; each blade being releasably retained in its slot by an inner end projection 18 seating in a corresponding socket 19. Additionally, a set screw 20 is threaded through the peripheral band 15 diagonally to bear against each blade to hold it in place.

25 30 35 The blades 17 have a straight horizontal lower cutting edge 21, and said blades are of a length so that they project somewhat beyond the peripheral band 15.

The blades 17 are driven, in the manner herein-after described, in order to impart rotation to the spinner 12; the latter being vertically adjustable by means of a lifting fork unit 26 secured to the upper end of the sleeve 22, said unit including a radial lever 27 extending from a cross shaft 28 in the housing 1. The cross shaft 28 carries the lifting fork units 26 for both rotary scrapers 11, 40 45 and said cross shaft is adjustable by an external

50 55 The spindle 23 is driven, in the manner herein-after described, in order to impart rotation to the spinner 12; the latter being vertically adjustable by means of a lifting fork unit 26 secured to the upper end of the sleeve 22, said unit including a radial lever 27 extending from a cross shaft 28 in the housing 1. The cross shaft 28 carries the lifting fork units 26 for both rotary scrapers 11, 55 and said cross shaft is adjustable by an external

hand lever 29 which cooperates with an adjustment quadrant 30. By manipulating the external hand lever 29 the rotary scrapers 11 may be raised or lowered at the selection of the operator.

A heavy-duty compression spring 31 surrounds the spindle 23 of each rotary scraper 11 between the bearing 25 and a collar 32 on the upper end of the sleeve 22, whereby to normally urge said rotary scraper downward to working position.

The rotary scrapers 11 are simultaneously driven, and at the same speed, by means of the following driving mechanism:

The spindles 23 are each fitted at their upper ends, and above the top plate 3, with a bevel pinion 33; said bevel pinions being driven by bevel gears 34 on a transverse drive shaft 35. The transverse drive shaft 35 is powered from an electric motor 36 by means of an endless drive 37, which drive is here in the form of an endless belt and pulley unit.

The drive shaft 35, in addition to driving the spindles 23, is extended and actuates a reversing gear box 38. From the reversing gear box 38, which includes a control lever 39, an endless drive 40, here in the form of an endless belt and pulley unit, powers one of the wheels 4, whereby the machine is self-propelled along the rails 6, but at relatively low speed.

Between the wheels 5 and the assembly of the rotary scrapers 11, the machine includes a transversely extending sanding drum 41, whose spindles 42 are carried at opposite ends in spring-suspended, but vertically adjustable, slide blocks 43. The slide blocks 43 each run in a rectangular supporting frame 44, with heavy-duty springs 45 above and below said block. An upstanding adjustment screw 46 works against the uppermost spring for the purpose of adjusting each block 43. By adjustment of the blocks 43 not only can the sanding drum 41 be leveled, but its pressure against the floor can be effectively regulated.

The sanding drum 41 is driven from the reversing gear box 38 by an endless drive 47, here in the form of an endless belt and pulley unit which extends between said gear box and one of the drum spindles 42.

When the machine is in operation, it is self-propelled along the bowling alley A from end to end thereof; the rotary scrapers 11 working to level the surface of the alley, and the sanding drum 41 acting to impart a fine finish thereto.

The diameter of the rotary scrapers 11 is such that they work slightly more than a transverse half of the alley A; the paths of the blades 17 at the outside partially overhanging the gutters 7, while the paths of the blades 17 at the inside lap each other, whereby no unscraped portion of the alley remains after passage of the machine.

In order to prevent the blades 17 of the separate spinners 12 from striking each other, corresponding blades on the different spinners are set to run about 45° apart.

With the described machine it is possible to impart a very excellent finish to the surface of a bowling alley, while at the same time maintaining the necessary accurate level of such alley.

5 A suction hood 48 overhangs the rotary scrapers 11 and approaches the sanding drum 41, to the end that scrapings or sanding dust may be prevented from blowing about. The suction hood 48 is connected to a suction pipe 49 which leads to 10 a suction fan 50 direct-connected to the electric motor 36. The suction fan 50 is adapted to discharge into a receiving bag (not shown).

While the herein described machine is adapted primarily for finishing bowling alleys, the machine may be put to advantageous use for surfacing and finishing wooden floors generally. In this event it is preferable that the flanged wheels 4 and 5 be substituted by flat-faced wheels.

From the foregoing description it will be readily seen that there has been produced such a device as substantially fulfills the objects of the invention, as set forth herein.

While this specification sets forth in detail the present and preferred construction of the device, 25 still in practice such deviations from such detail may be resorted to as do not form a departure from the spirit of the invention, as defined by the appended claim.

Having thus described the invention, the following is claimed as new and useful, and upon which Letters Patent are desired:

30 A spinner for a floor finishing machine comprising a hub, a vertical spindle upstanding from the hub, spider legs projecting radially of the hub, 35 a peripheral band supported about the outer ends of the spider legs, certain of the legs being provided with radially disposed slots opening downwardly and the inner end of each slot terminating in a socket formed in the leg, a blade fitting 40 in each slot, the blade being provided with a projection at its inner end fitting in the adjacent socket, and a set screw projecting diagonally through the band into engagement with each blade.

GIOVANNI PAROVEL.
